UNITED STATES PATENT OFFICE.

JAMES G. LUTES, OF HOOPER, AND FRANK E. HARDY, OF HILLYARD, WASHINGTON.

BLEED-VALVE.

1,109,774.

Specification of Letters Patent.

Patented Sept. 8, 1914.

Application filed December 9, 1913. Serial No. 805,561.

To all whom it may concern:

Be it known that we, JAMES G. LUTES and FRANK E. HARDY, citizens of the United States, residing at Hooper and Hillyard, respectively, in the counties of Whitman and Spokane and State of Washington, have invented new and useful Improvements in Bleed-Valves, of which the following is a specification.

10 This invention relates to improvements in bleed valves for exhausting the train line of a car after the same has been disconnected from the train.

It is one of the objects of this invention to 15 provide an improved bleed valve, which will remain in an exhaust position after it has once been opened so as to avoid the necessity of holding it open until the auxiliary reservoir has been completely exhausted.

20 A special novel feature of the invention consists in providing a bleed valve, which is openable into the path of the air to be exhausted so that the bled air will act against the valve to hold the same open until the 25 brake system of the car has been exhausted.

A further novel feature consists in embodying the foregoing feature in the form of a valve, which will automatically close by gravity when the air has been exhausted, so 30 that when the car is again connected with a train its brake system will be ready for a charge from the train line.

Other features of novelty will be more 35 fully described in connection with the accompanying drawing, and will be more particularly pointed out in and by the appended claims.

In the drawing:—Figure 1 is a view in 40 side elevation of an auxiliary reservoir and brake cylinder of a car or railway vehicle, showing the application of one form of the device of our invention thereto. Fig. 2 is an end view thereof. Fig. 3 is a perspective view of our improved bleed valve structure 45 detached from the air brake structure. Fig. 4 is a sectional view on line 4—4 of Fig. 3, showing the valve closed. Fig. 5 is a view similar to Fig. 4, showing the valve open. Fig. 6 is a sectional view on line 6—6 of Fig. 4. Fig. 7 is a detail view of one form 50 of valve closure detached from the bleed valve.

Like characters of reference designate 55 similar parts throughout the different figures of the drawing.

An air brake structure is illustrated com-

prising an auxiliary reservoir 1 and a brake cylinder 2. In the brake cylinder 2 a piston 3 is indicated having a piston rod 4, which is designed for connection with certain brake rods or levers, not shown. A spring 5 normally acts to retain the piston 3 in a retracted position. A pipe 6 leads to the car train line and will be provided with the usual triple valve not herein shown.

The device of our invention includes a bleed valve casing structure 7, which is provided with an exteriorly threaded extension 8 adapted to be turned into a bore tapped into one part of the structure of the air 60 brake, which as shown, is the auxiliary reservoir 1. The extension 8 is provided with a bleed air exhaust passage 9, which extends longitudinally thereof to a point internally of the structure 7 where it turns at 10 and 65 delivers to a valve chamber 11. We have shown the valve chamber 11 closed or provided with a flush plate 12, having an outlet 13 opening to atmosphere. The flush plate 12 constitutes a valve seat on which a 70 valve 14 is adapted to be engaged to act as a valve closure for the valve outlet 13. We have shown the valve 14 in the form of a flap valve, which is arranged to be opened against a portion 15 of the casing structure 7, which acts as a stop limiting opening 75 movement of said valve. The stop for said valve is so located that the latter will not attain a vertical position when moved to a full outlet or open position, so that provision will 80 be made for automatic closure of the valve by gravity.

The valve 14 is provided with a sleeve 16, which fits between wall portions 17, so that lateral movement will be restricted. The 95 sleeve 16 loosely embraces a valve operating rod 18, which is journaled in the casing structure 7 and which projects therefrom, as shown in Fig. 6. A packing gland 19 may be provided to insure an air tight closure 100 about the valve rod. The projecting end 20, of the valve rod, is preferably polygonal, and we mount thereon, centrally of its ends, a lever 21. Operating rods 22 and 23 are attached to the opposite ends of said lever 21, 105 so as to extend to opposite sides of the car for connection with the operating cords, or for operation direct. Rod 22 is slideable in a hanger bearing 24, which is pendant from a car sill 25. A shoulder 26 forms an abutment between which and the bearing 24 is interposed a spring 27, which functions to 110

normally maintain the rod 22, and consequently the lever 21, in the position shown in Fig. 2. The outer end of the rod 22 is hooked, as at 28.

5 One end of the sleeve, as indicated at 29, is offset to form shoulders 30 and 31. The rod 18 is provided with a pin 32, which is adapted to engage said shoulders to provide for a lost motion connection between the rod 18 and the valve 14. When the rod 22 is pulled, the pin 32 will engage shoulder 30 and lift the valve 14 from the position shown in Fig. 4 to the position shown in Fig. 5. The train men may then release the rod 22 and under action of its spring 27, the said rod will immediately be retracted to a normal position. The space between the shoulders 30 and 31 permits of this retractive movement without in any way influencing or altering 20 the position of the valve.

It will be noted by reference to the arrows shown in Fig. 5 that the valve 14 is openable into the path of the exhausted or bled air so that the latter will function to 25 hold the bleed valve open after it has been manually moved to an open position. The stop 15 will limit opening movement of the valve 14 both under manual operation and the action thereagainst of the exhausting or 30 bled air. In the embodiment shown, the valve 14 is not only located so that when it is opened it will lie in the path of the bled air, but in addition, it is so located and disposed with respect to passage 10 and outlet 13 that it will deflect the bled or exhausting air from the course that it would naturally take in discharging from passage 10, angularly through outlet 13, thereby serving to insure retention of the valve in 40 an open position, after once being open, until the air from the auxiliary reservoir 1 has been exhausted. By relieving pressure in the auxiliary reservoir 1, the spring 5 will retract the brake piston 3 and withdraw 45 brake pressure, this operation taking place after a car has been disconnected from a train.

It is well known that the reservoir 1 is connected to the train line by a triple valve 50 and that when it is desired to set the brakes, the train line is opened to atmosphere with the result that the triple valve is operated for passage of air from the auxiliary reservoir 1 into the brake cylinder to set the 55 brake shoes. If the cars come off from the train, the only way to release the brakes is to operate the bleed valve. In many constructions it is necessary for the train men to hold the bleed valve open, so as to exhaust the auxiliary reservoir and this is not only hazardous by reason of the fact that it involves the frailty of a human element, but it also involves a waste of time and often includes an element of danger.

65 In the present construction, the bleed

valve will remain open, after once being opened, until the air is exhausted, and then it will automatically close, and when it is closed, it will be subject to air pressure from the reservoir 1 in a manner to securely 70 maintain it in a closed position, thereby avoiding leakage which now results when the valve is not closed, subsequent to bleeding the system.

It is believed that the operation and utility of our invention will be fully understood from the foregoing description, and while we have herein shown and described one specific embodiment of our invention, we do not wish to be limited thereto except for 80 such limitations as the claims may import.

We claim:—

1. As a means for bleeding an air brake system, an air brake structure provided with a bleed outlet portion opening to atmosphere, and closure means for said outlet portion openable into the path of and deflecting the bled air from its normal course to maintain said closure means in an open position by engagement of such air thereagainst, substantially as described. 85

2. As a means for bleeding an air brake system, an air brake structure provided with a bleed outlet portion opening to atmosphere, and a hinged valve closure openable into the path of the bled air to maintain said valve in an open position by engagement of such air thereagainst, substantially as described. 95

3. As a means for bleeding an air brake system, an air brake structure provided with a bleed outlet portion opening to atmosphere, and a hinged closure interposed in said outlet portion to be opened into the path of the bled air and held in a closed position under pressure through said outlet portion, substantially as described. 100

4. As a means for bleeding an air brake system, an air brake structure provided with an outlet portion opening to atmosphere, a hinged flap valve interposed in said outlet portion in a position to be held open or closed under pressure therethrough, and means having a lost motion connection with said flap valve for moving the same into the path of the bled air and into an open position, substantially as described. 110

5. As a means for bleeding an air brake system, an air brake structure having a bleed outlet portion opening to atmosphere, and hinged valve means actuated to be held in an open position by bled air passing through said portion, substantially as described. 120

6. As a means for bleeding an air brake system, an air brake structure having a bleed outlet portion opening to atmosphere, a hinged bleed valve interposed in said outlet portion to be opened into the path of the bled air, a valve rod loosely disposing said valve in said outlet portion and having a 125 130

lost motion connection with said valve, means for operating said rod to swing said valve into an open position into the path of the bled air, and means for returning 5 said operating means to a normal position without altering the position of said valve, substantially as described.

In testimony that we claim the foregoing

as our own, we hereby affix our signatures in the presence of two subscribing witnesses. 10
